UNITED STATES PATENT OFFICE.

GEORGE H. WARING, OF INDIANTOWN, NEW BRUNSWICK, CANADA, AS
SIGNOR TO HIMSELF AND CHARLES MILLER, OF SAME PLACE.

FISH-PLATE.

SPECIFICATION forming part of Letters Patent No. 239,898, dated April 5, 1881.

Application filed October 26, 1880. (No model.)

To all whom it may concern:

Be it known that I, GEORGE H. WARING, of Indiantown, New Brunswick, Canada, have invented a new and Improved Fish-Plate, of 5 which the following is a specification.

The object of this invention is to provide an improved fish-plate for use on railroads, whereby the ends of the rails will be more securely held and the transverse strain upon the holding bolts entirely avoided.

The invention consists of a fish-plate having around its bolt-holes projecting thimbles whose length is equal to half the thickness of a rail-web, so that when two plates are applied 15 to opposite sides of a rail the thimbles entering the corresponding holes in the web will meet in the center thereof; and it consists, further, of a combination of the plates and thimbles with the rail-web.

Figure 1 represents a side elevation of a fish-plate fastened to a rail-web. Fig. 2 is a longitudinal section of the same on line xx , Fig. 1. Fig. 3 is a transverse section of the same on line yy , Fig. 2.

Similar letters of reference indicate corresponding parts.

In the drawings, A represents a fish-plate, consisting of a flat plate, A', provided on one face with projecting thimbles $a a$, of such an 30 external diameter as to fit into the corresponding holes, b , made through the rail-webs B, so

that when the said rail-webs B contract or expand said thimbles $a a$ support all the strain. Said thimbles $a a$ are half as long as the thickness of the web B, so that when two fish-plates, 35 A A, are fitted upon rails as shown, their thimbles $a a$ meet in the centers of the holes $b b$. The bolts C C are then inserted through the thimbles $a a$, and held in place by nuts $c c$, as shown.

It will be seen the bolts C C are entirely protected from lateral strain, because of being increased in the thimbles $a a$. Hence said bolts C C will not readily become loose, and will last much longer, and are more easily inserted and 45 removed.

Having thus described my invention, I claim as new and desire to secure by Letters Patent—

1. A fish-plate constructed substantially as 50 herein shown and described, consisting of plate A', provided with thimbles $a a$, as set forth, whereby the fish-plate bolts are protected from lateral strain, as set forth.

2. The combination, with the rail-web B, of 55 the fish-plates A', thimbles $a a$, and nuts and bolts C c, substantially as herein shown and described.

GEORGE HART WARING.
